UNITED STATES PATENT OFFICE

ADOLPHE VEILLEUX, OF ST. MARIES, IDAHO

LOG DECKER

Application filed November 16, 1926. Serial No. 148,638.

The invention is a device for loading or piling logs or the like, which is adjustable to two positions.

The object of the invention is to provide a device upon which logs may be readily placed, which will raise the logs and dump them upon a car, truck or pile.

Another object of the invention is to provide an adjustable platform having one end elevated and conveyor chains for conveying objects up to said platform.

Another object of the invention is to provide a device for raising logs which may readily be adjusted to different positions.

15 A further object of the invention is to provide means for operating conveyor chains on an adjustable inclined platform from the adjustable end.

And a still further object of the invention 20 is to provide an adjustable log decking platform which is of a simple and economical construction.

With these ends in view the invention embodies a frame having skids on the bottom 25 thereof, an adjustable inclined frame with conveyor chains thereon mounted on the said skid frame, levers for raising the said inclined frame, and automatically adjustable driving means for operating the conveyors 30 on the said adjustable frame.

Other features and advantages of the invention will appear from the following description taken in connection with the drawings, wherein:—

35 Figure 1 is a longitudinal section through the center of the device.

Figure 2 is a plan view showing the adjustable frame with the chains omitted.

40 Figure 3 is a cross section through the device looking toward the elevated end.

In the drawings the device is shown as it would be made wherein numeral 1 indicates the base frame, numeral 2 the inclined frame, and numeral 3 the main shaft through which 45 the device is operated.

The base frame 1 is made with two longitudinal skids 4 and 5 which are connected by a cross member 6 at the front, and other members 7 and 8 at the rear. It is also understood that the frame 1 may be made in any

other desired manner and of any suitable material.

The inclined frame 2 is made with two side members 9 and 10, which may be held together with cross members 11 and diagonal braces 12. The lower end of the frame 2 is pivotally attached by plates 13 and bolts 14 to the members 4 and 5 of the base. And at each end of this frame are transverse shafts 15 and 16 upon which sprockets 17 are mounted over which chains 18 with projecting fingers 19 are placed. The shaft 16 is provided with a bevel gear 20 at the center, which is held in a bracket 21 and which meshes with a bevel gear 22 which is also held in a bracket and mounted upon a vertical shaft 23. The lower end of the vertical shaft 23 is square from the point 24 to the lower end and this is slidably mounted in a square opening in the socket 25, as shown. At the lower end of the socket 25 is a bevel gear 26, and it will be observed that this end of the socket is held in a bearing 27 in a bracket 28, as shown in Figure 3. The bracket 28 is also mounted upon a shaft 29 which is provided with a bevel gear 30 that meshes with the gear 26. The shaft 29 is rotatably mounted in bearings 31 on the base frame 1 and at one end of the shaft is a pulley 32 over which a belt 33 from a pulley 34 on an engine 35 passes, so that as the engine rotates it will rotate the shaft 29 through the pulleys and as this shaft rotates it will rotate the shaft 16 through the gears, as hereinbefore described, and the shaft 16 will operate the sprockets 17, which in turn operate the conveyor chain 18.

On the shaft 29 is a drum 36, which is operated by a clutch 37 through levers 38 and 39, and from this drum a cord 40, which is wrapped around the drum, passes over a pulley 41 on a shaft 42 and is then attached to a rod 43, which is held in the ends of levers 44, as shown in Figure 3. The levers 44 are pivotally mounted on a shaft 45 in standards 46 and 47, and it will be observed that the upper ends 48 of the levers bear against channels 49 on the under side of the beams 9 and 10 of the inclined frame 2. It will be observed that as the clutch is thrown in and the drum rotated it will pull the cord 40

downward, which will draw the levers 44 downward and at the same time force the levers 48 upward, which will raise the inclined frame 2 to the position shown in dotted lines in Figure 1. A bolt 50, which is slidably held on one of the standards in bearings 51, may then be moved inward so that it will engage the ends of the levers 44 and hold them in this position, with the frame in the 10 position shown in dotted lines. The clutch may then be released until it is desired to lower the said frame.

At the forward ends of the skids 4 and 5 are rollers 52 and 53 which are held in 15 bearings 54, as shown. It will be observed that the logs will first strike these rollers and these rollers will assist the operator in moving the logs to such a position that they will be gripped by the chain.

20 It will be understood that changes may be made in the construction without departing from the spirit of the invention. One of which changes may be in the design or arrangement of either of the frames, another 25 may be in the use of other means for raising or holding the inclined frame, and still another may be in the use of other means for operating the chains on the inclined frame.

The construction will be readily understood 30 from the foregoing description. To use the device it may be arranged as shown, and it will be observed that as the motor is started it will cause the chains to operate and as logs are placed upon the device they will 35 readily be moved up the inclined platform and dumped off of the upper end. It will also be observed that as the logs reach the elevation of the platform as shown in full lines, the platform may readily be raised to the 40 position shown in dotted lines so that logs may be piled higher. The device may be made of any suitable dimensions so that it may handle logs of any size.

Having thus fully described the invention, 45 what I claim as new and desire to secure by Letters Patent, is:—

In a log decking inclined elevator, the combination of a skid platform comprising a pair of longitudinal skids, rollers at the 50 forward ends of the said skids, a shaft rotatably mounted behind the said rollers forming the tail shaft of an endless chain conveyor, a head shaft at the opposite end of the said conveyor, a frame in which the said 55 head and tail shafts are mounted, means for mounting the said frame upon the said skids, means for elevating the head shaft end of the said frame, and means for driving the head shaft from the said skids, said driving means 60 driving the central part of the said shaft and positioned within the limits of the said device.

In testimony whereof he affixes his signature.

65 ADOLPHE VEILLEUX.
